SHOE AND THE LIKE

Serge Brandel, Villefranche-sur-Mer, Alpes-Maritimes, and Henri Perrot, Paris, France; vested in the Alien Property Custodian

Application August 8, 1939, Serial No. 289,023
In France May 22, 1939

2 Claims. (Cl. 36—3)

Our invention relates to shoes, sandals and the like. A primary object of the invention is to provide for a thorough ventilation of the foot.

By way of non-limitative examples, two embodiments of a shoe according to our invention have been shown in the accompanying drawing.

In said drawing:

Fig. 1 is a side view of a first embodiment;

Fig. 2 is a transverse section of the shoe taken on line II—II of Fig. 1 at an intermediate point of the sole and looking towards the heel, and

Fig. 3 is a perspective view of another embodiment.

As shown in Figs. 1 and 2, the shoe comprises a framework 1, in this case in one piece, made of hollowed-out wood or of moulded plastic material, with which the heel 2 is also integral. Said framework is hollowed-out in the part corresponding to the place for the sole of the foot and is composed at that spot of only a border 3 which follows the outer contour of the sole of the foot. On the upper face of said border 3 is fixed the perforated element 4 for supporting the foot, which element is in this case formed of plaited straw. On the under face of the border 3 and to form a surface for contact with the ground is fixed a leather covering 5 formed by a strip or by a plurality of superposed strips. The upper part of the shoe may be constructed in any manner and has not been shown.

It will be seen further that in this example, all the interstices of the plaited element 4 open into a single common cavity 6 which communicates with the atmosphere. On the other hand, the two sides of the border 3 are provided with holes 7 which open into said cavity 6. This cavity 6 acts as a common collector for said interstices.

In the embodiment shown in Fig. 3, the framework is similar to the one described above but is covered on the outside with sheets 8 of plastic material and the perforated supporting element is formed by a sheet 9 of plastic material, over the surface of which are distributed perforations 10.

The framework may also be made of any appropriate material which is moulded, cut or shaped in any manner whatsoever. It may be made of superposed layers for example of cork and/or leather. A rugged, light framework is thus obtained which is nevertheless fairly flexible.

The perforated element for supporting the sole

of the foot may also be formed by wickerwork similar to that of wicker seats, the border formed by said framework acting as the frame of said seats. A bearing element thus formed is very strong, light and inexpensive and enables the sandals to be cheaply constructed. It may also consist of perforated straps, strips, bands or plates somewhat spaced apart and fixed on said border of the skeleton.

10 The surface whereby said framework contacts the ground may be covered with leather, sponge rubber, crepe, cork or any other similar material that is generally used for this purpose.

15 The outer covering of the framework may advantageously be made of lacquered rushes arranged side by side as shown in Fig. 1 at the heel part.

What we claim is:

- 20 1. In a shoe or sandal a relatively high heel, a rigid frame integral with an upper portion of said heel and extending downwardly and forwardly from the heel in an arcuate shape to provide a sole part for the shoe, said frame being relatively thick and hollow forwardly of the heel so as to provide a rigid border shaped in accordance with the lateral contour of a foot, the upper edges of said frame being shaped like the bottom face of the foot, a yieldable apertured foot-supporting sheet extending across the hollow frame and secured to the upper edges of said border for yieldingly supporting the foot, and said border having relatively large holes extending transversely therethrough at spaced intervals around the frame.
- 25 30 35 2. In a shoe or sandal a relatively high heel, a rigid frame integral with an upper portion of said heel and extending downwardly and forwardly from the heel in an arcuate shape to provide a sole part for the shoe, said frame being relatively thick and hollow forwardly of the heel so as to provide a rigid border shaped in accordance with the lateral contour of a foot, the upper edges of said frame being shaped like the bottom face of the foot, a plaited straw sheet having relatively large interstices therein for yieldingly supporting the sole of the foot extending over the hollow frame and secured at its marginal edges to the upper edges of said border and substantially flush with the top of said heel.
- 40 45
